Primary Examiner — Marie D. Fast Horse*Assistant Examiner* — Jennifer Sierra Yosinski(74) *Attorney, Agent, or Firm* — Mohr Intellectual Property Law Solutions, PC(57) **CLAIM**

The ornamental design for a tool storage rack, as shown and described.

DESCRIPTION

FIG. 1 is a top perspective view of a tool storage rack showing my new design, shown with an unclaimed CNC holder tool supported in the tool storage rack.

FIG. 2 is a bottom perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right-side elevation view thereof; and,

FIG. 8 is a left-side elevation view thereof.

Broken lines in the drawings depict an environmental CNC tool holder that forms no part of the claimed design.
